UNITED STATES PATENT OFFICE.

GEORGE M. ELLIS, OF ARTHUR, IOWA.

ACETYLENE-GAS GENERATOR.

1,135,002.

Specification of Letters Patent. Patented Apr. 13, 1915.

Application filed March 3, 1914. Serial No. 822,188.

To all whom it may concern:

Be it known that I, GEORGE M. ELLIS, citizen of the United States, residing at Arthur, in the county of Ida and State of Iowa, have invented certain new and useful Improvements in Acetylene-Gas Generators, of which the following is a specification.

My invention relates to acetylene gas apparatus, and particularly to the means for generating acetylene gas.

One object of my invention is the provision of a very simple generating device particularly adapted either for lighting purposes or for use with an oxo-acetylene welding torch.

A further object of the invention is to provide an acetylene gas generator so constructed that a constant pressure of gas is given so long as any carbid remains in the carbid container.

A further object in this connection is to provide an automatic control of the gas generator whereby when the pressure falls below a certain point the generation of the gas will immediately commence and when the pressure rises beyond a certain point this generation will cease.

A further object is to improve and simplify the details of construction and to provide means whereby fresh carbid may be readily placed within the generator and the residue removed.

Other objects will appear in the course of the following description.

Figure 1 is a vertical sectional view of my improved generator. Fig. 2 is a perspective detail view of the carbid holder opened up. Fig. 3 is a perspective view of the carbid basket. Fig. 4 is a perspective view of one of the apron sections. Fig. 5 is an enlarged section of the valve 11 and valve casing.

Corresponding and like parts are referred to in the following description and indicated in all the views of the accompanying drawings by the same reference characters.

My improved generator consists of two chambers A and B, each of these chambers consisting of a section of pipe, each section being six inches in diameter and two feet long. The pipe 2 of the section A is closed at top and bottom by caps 3, the upper cap being provided with a pressure gage 4 of any suitable construction. A water pipe 5

enters the chamber A adjacent its upper end, this water pipe being provided with a valve whereby the entrance of water may be controlled. The chamber B likewise consists of a section of pipe designated 2^a closed at its lower end by means of a screw-threaded cap 3^a and at its upper end by means of a cap 6. This cap is formed of an annulus 7 interiorly screw-threaded for engagement with exterior screw threads on the pipe section 2^a to which annulus is bolted a plate 8 provided with a safety valve and with a pressure gage. The pipe sections A and B are connected at the bottom by a pipe line 9 including a union, a globe valve 10 and a check-valve 11, which check-valve has a small hole drilled through it whereby to let the water rise slowly in the chamber B so as to prevent too much of the carbid carried in said chamber from being dampened at one time, and thus preventing an over pressure. The check-valve, however, permits water to escape quickly from the chamber B when the pressure in this chamber has increased beyond the said point.

Disposed within the chamber B is a carbid container. This as illustrated is circular in section and made in two lateral halves, as shown clearly in Fig. 2, these half sections being hinged to each other. One of the half sections is designated 12 and the other 12^a, the hinges being designated 13. The lower portion of these sections 12 and 12^a are perforated as at 14 for the inlet of water. The sections 12 and 12^a when closed form a cylindrical hollow body less in diameter than the diameter of the pipe section 2^a and adapted to rest upon the bottom cap 3^a, as shown clearly in Fig. 1. Mounted upon the sections 12 and 12^a are the brackets 15 for supporting the carbid basket and disposed below these brackets is an apron made in two sections, each of these sections being designated 16. Each section is constructed as shown in Fig. 4, of a semi-circular plate flanged at its upper end as at 17, this flange being adapted to be riveted to the sections 12 and 12^a. The body portion of each apron section extends down parallel to the sections 12 and 12^a and these aprons are of sufficient extent to protect the perforations 14 and prevent the residue of the carbid holder from plugging up or clogging the holes or perforations 14. The apron permits the used carbid to drop

down into the bottom of the carbid holder from which it may be removed when the generator is cleaned.

Supported upon the brackets 15 is a carbid basket 18 illustrated in Fig. 3. This basket embodies a perforated or reticulated side wall, a perforated or reticulated bottom and a perforated or reticulated centrally disposed screen which is designated 19 extending up through the middle of the basket, the upper end of the basket being open. The basket has a diameter less than the diameter of the carbid holder formed of the sections 12 and 12^a so that water may pass freely up on the outside of the basket as well as up through the perforated or reticulated tube 19 and through the bottom of the basket.

The operation of my invention is as follows:—In starting to generate gas, carbid is placed in the top part of the container, that is, within the basket 18. The carbid basket is then placed within the holder formed of the sections 12 and 12^a and the holder and basket are inserted in the generating chamber B. The top cap 6 is then screwed down. The globe valve 10 in the pipe line is then opened and water which has previously been allowed to enter the chamber A is allowed to flow into chamber B until water reaches the level of the test cock 20 therein. The globe valve is then closed and the section A is filled with water up to the pipe 5 which is connected to a street L, or to any other suitable source of supply. Compressed air is then forced into the upper end of the chamber A, above the water by means of any suitable air pumping apparatus which may be connected to a nipple 21 projecting from the chamber A. When the globe valve 10 is now opened the water in the generating chamber B will be forced upward by the pressure behind the water in the chamber A until the water in the chamber B reaches the carbid, whereupon gas is generated. This increases the pressure in the upper portion of the chamber B and forces the water away from the carbid, the check-valve 11 readily permitting the return flow of water. The return flow of water will, of course, further compress the air in the upper portion of the chamber A. When the pressure in the generator B becomes reduced then the water again rises into contact with the carbid in the basket. It will, of course, be noted that to insure against the possibility of gas getting into the chamber A, the chamber B should be filled with a column of water equal to or somewhat greater than the area of the column in the upper portion of the chamber A, which is filled with air.

It is to be understood that I may dispense with the chamber A in some cases and connect the pipe 9 directly with a source of water under pressure. This will operate in much the same manner. When the pressure

of gas is reduced in the upper portion of the chamber B the pressure of water in the pipe 9 will force the water in the chamber B up into contact with the carbid. When the pressure of gas in the upper portion of the chamber increases, the column of water in the chamber B will be forced down against the pressure in the pipe 9.

The check valve 11 operates in the following manner: It is so placed that the water passes slowly through the perforation toward the carbid chamber when the pressure of the compressed air in the water chamber is greater than the pressure of gas in the generating chamber, but when the pressure of gas in the generating chamber becomes greater than the air pressure in the water chamber and the flow of water is toward the water chamber, the check valve opens and allows the water to escape rapidly from the generating chamber while the check valve adds to the easiness with which the machine may be started. It is to be understood that I do not wish to be limited to the use of this check valve as in many cases it may be removed.

I have found in practical operation that the pressure in the chambers A and B remains practically constant with my apparatus until the carbid is all used. It will be seen that the control of this apparatus is automatic and that the device is so simple as not to easily get out of repair or become inoperative.

Having thus described the invention what is claimed as new is:—

1. An acetylene gas generator including a generating chamber, means for supporting carbid in the upper portion thereof, a water pipe entering the lower portion of the generating chamber, a check-valve in said pipe, said valve opening from the generating chamber and being provided with a perforation, said pipe being connected to a source of water under pressure, the check-valve permitting back flow of water when the gas pressure in the generating chamber is greater than the water pressure.

2. An acetylene gas generator including a tubular generating chamber closed at its opposite ends by caps, one of said caps being removable, a carbid holder disposed within the generating chamber and less in diameter than said chamber, said holder being formed of oppositely disposed semi-cylindrical sections hinged to each other, the bottom of the holder being closed and the top of the holder being open and the lower portion of the holder perforated for the admission of water, brackets disposed within the holder, and a carbid basket removably mounted upon said brackets and supported adjacent the upper end of the holder.

3. An acetylene gas generator including a generating chamber, having a water inlet

- pipe at its lower end, a cap closing the upper end of the chamber, a carbid holder removably mounted within the chamber and consisting of hinged sections, the lower portion of the holder being perforated for the admission of water, a sectional apron mounted in the interior of the holder and extending downward over said perforations but spaced from the wall of the holder, and a removable carbid basket disposed in the upper portion of the chamber.
5. An acetylene gas generator including a tubular generating chamber closed at its opposite ends by caps, one of the caps being removable, a carbid holder disposed within the generating chamber and less in diameter than said chamber, said holder being formed of oppositely disposed semi-cylindrical sections hinged to each other, the bottom of the holder being closed, the top of the holder being open, the lower portion of the holder being perforated for the admission of water, an apron extending over said perforations and spaced from the wall 10 of the holder, brackets disposed within the holder, and a carbid basket removably mounted upon said brackets.
15. An acetylene gas generator including a generating chamber closed at its opposite ends by caps, one of the caps being removable, a carbid holder disposed within the generating chamber and less in diameter than said chamber, said holder being formed of oppositely disposed semi-cylindrical sections hinged to each other, the bottom of the holder being closed, the top of the holder being open, the lower portion of the holder being perforated for the admission of water, an apron extending over 20 said perforations and spaced from the wall of the holder, brackets supported within the holder, and a carbid basket mounted upon said brackets.
25. An acetylene gas generator including a generating chamber and a water chamber, a pipe connecting the lower ends of the two chambers, a check-valve in said pipe opening from the generating chamber and said check-valve being perforated, a carbid
- holder disposed in the upper portion of the generating chamber, and means whereby air may be compressed into the upper portion of the water chamber.
30. 6. An acetylene gas generator including a generating chamber, formed of a section of pipe, closed at one end and having a removable cap at the other end, a water chamber formed of a section of pipe closed at opposite ends, a pipe connecting the two chambers at their lower ends, a check-valve in said pipe opening from the generating chamber and being perforated, a globe valve in the pipe, means in the upper end of the water chamber whereby air may be compressed therein, means for admitting water to the water chamber, a removable carbid holder disposed within the generating chamber and comprising a cylindrical member formed in opposed hinged sections, the lower end of said holder being perforated for the admission of water, an apron covering said perforations and spaced from the wall of the holder, brackets supported within the holder, and a removable carbid basket mounted upon said brackets.
35. 40. 45. 50. 55. 60.

In testimony whereof I affix my signature in presence of two witnesses.
